(57) **CLAIM**

The ornamental design for ironing board legs, substantially as shown and described.

DESCRIPTION

FIG. 1 is a perspective view of my new design in its environment, namely, mounted to an ironing board. The ironing board and iron rest are shown in broken lines for illustrative purposes only, and form no part of the claimed design;

FIG. 2 is a front elevation view of the design of FIG. 1;

FIG. 3 is a rear elevation view of the design of FIG. 1;

FIG. 4 is a right side elevation view of the design of FIG. 1;

FIG. 5 is a top view of the design of FIG. 1;

FIG. 6 is a bottom view of the design of FIG. 1;

FIG. 7 is a top view of the design of FIG. 1 in the folded condition; and,

FIG. 8 is a bottom view of the design of FIG. 1 in the folded condition.
